(57) **CLAIM**

The ornamental design for a cap of cartridge for component extraction, as shown and described.

DESCRIPTION

FIG. 1 is a perspective view of the top, front and right side of a cap of cartridge for component extraction showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a cross-sectional view thereof taken at the direction of line 8—8 of FIG. 3;

FIG. 9 is a cross-sectional view thereof taken at line 9—9 of FIG. 3;

FIG. 10 is a cross-sectional view thereof taken at line 10—10 of FIG. 3;

FIG. 11 is a cross-sectional view thereof taken at line 11—11 of FIG. 3;

FIG. 12 is a front elevational view thereof without filter;

FIG. 13 is a cross-sectional view thereof taken at the direction of line 8—8 of FIG. 4, without filter; and,

FIG. 14 is an exploded perspective view thereof while in use.

The portions shown in broken lines are for environmental purposes only and form no part of the claimed design.
